UNITED STATES PATENT OFFICE.

CHARLES PHELPS, OF OSKALOOSA, IOWA.

SECTIONAL FURNACE.

1,278,379.

Specification of Letters Patent. Patented Sept. 10, 1918.

Application filed December 27, 1912. Serial No. 738,834.

To all whom it may concern:

Be it known that I, CHARLES PHELPS, a citizen of the United States, residing at Oskaloosa, in the county of Mahaska, and 5 State of Iowa, have invented a certain new and useful Sectional Furnace, of which the following is a specification.

The object of my invention is to provide a furnace of the class known as sectional furnaces and in which each of the sections 10 is divided into two half sections, each half section being complete in itself and said half sections being interchangeable for either side of the furnace so that when it 15 becomes necessary to repair or replace a broken or defective part the operator need only remove the half section and replace it with a new half section device effecting a great economy in the time, labor and expense of making repairs.

More specifically it is my object in this connection to provide an improved form of section especially designed for the front and the rear of a furnace and so constructed 25 and arranged that a half section may readily and easily be substituted for any one of the four half sections of a furnace front or a furnace rear.

Another object is to provide furnace half 30 sections of this kind in which there is a complete and independent circulation of water through each half section.

Another object is to provide furnace sections of this class by the use of which a complete furnace may be made including not 35 only the boiler portion but the fire grate supporting portion and the ash pit portion so that when a furnace is changed in size by the addition or removal of sections, no 40 other work such for instance as the laying of foundations or of brick walls for the ash pit need be constructed.

A further object is to provide a device 45 to be used in the nature of an attachment for sectional furnaces of this class, whereby an ordinary hot water furnace may be changed into a steam furnace and which attachment may be readily and easily removed or replaced.

50 My invention consists, in certain details, in the construction, arrangement and com-

bination of the various parts of the device, whereby the objects contemplated are attained, as hereinafter more fully set forth, pointed out in my claim and illustrated in 55 the accompanying drawings, in which:

Figure 1 shows a rear end elevation of a sectional boiler furnace embodying my invention and having the steam generating chamber applied thereto, a part thereof being broken away to show the interior.

Fig. 2 shows a top or plan view of same.

Fig. 3 shows a sectional, perspective view illustrating one of the rear furnace members and also part of an adjacent intermediate furnace member.

Fig. 4 shows a detail, horizontal, sectional view of same taken on a line through the water circulating openings thereof near the top.

Fig. 5 shows a perspective view of one of the rear furnace members complete.

Fig. 6 shows a perspective view of one of the members of the intermediate furnace section embodying my invention.

Fig. 7 shows a front elevation of two furnace half sections provided with the necessary attachments for forming a furnace front.

Fig. 8 shows a rear elevation of two furnace half sections arranged together for forming a rear furnace section, the attachments necessary therefor being omitted, which attachments however are illustrated in Fig. 1.

Fig. 9 shows an enlarged, detail, sectional view illustrating the upper portion of one of the furnace half sections to show the circulating openings, and

Fig. 10 shows an enlarged, detail, sectional view illustrating a hand hole cover for the circulating openings in the front sections.

Referring to the accompanying drawings, I shall first describe the front and rear furnace half sections. Each of these, as will be seen by reference to Figs. 3 and 5, comprises a hollow rectangular body portion 10 having on its inner edge a rectangular recess 11 near its top provided with perforated lugs 12 at its corners. These lugs are preferably spaced about midway between

the sides of said body portion. Below the rectangular recess 11 another similar recess 12^a having thereon perforated lugs 12^b, similar to the lugs 12 and at the lower inner corner of the body portion 10 is an angular recess 12^c having perforated lugs 12^d at the corners thereof.

The inner edge of the body portion 10 is provided with a vertically arranged rib 13, the ribs of two adjacent half sections 10 being designed to fit together in the manner illustrated in Fig. 2.

Near the upper outer corner of each of the body portions 10 on both sides are the 15 circulating openings 14.

In order to couple one of these half sections to an adjacent half section, I provide the perforated lug 15 at the top above the adjacent circulating opening 14 and near 20 the bottom is a perforated lug 16, which lugs may be connected together by means of bolts 17 arranged in the manner shown in Fig. 2. Below the lower circulating openings 14 are the flanges 18 which extend 25 downwardly and which are designed to rest upon a suitable flat base such, for instance, as a concrete floor.

When two of these half sections are intended to be used to form a furnace front 30 they are connected with each other by means of the plates 19 shown in Fig. 7, which plates are secured to the perforated lugs in the rectangular openings. The upper plate 19 is provided with a clean-out door 20, the 35 central one with a fire door 21 and the lower plate with a draft door 22 and an ash door 24. In addition to this the circulating openings 14 at the front are preferably covered by means of plates 25 held in place by the 40 bolts 26 engaging the arches 27 on the interior and being provided with the nuts 28 on the exterior. In addition to this upright lugs 29 may be provided, as shown in Fig. 7, and these lugs may be connected by means 45 of bolts 30.

In the event that these half sections are intended to be used at the rear of the furnace, a plate 31 is provided in the upper rectangular opening, which plate is provided with a central circular opening 32 for a flue pipe. The central rectangular opening is covered by a solid plate 33 and the lower rectangular opening by a solid plate 34, all of which are bolted to the perforated 55 lugs. Obviously any one of these half sections for the front and rear of the furnace may be removed and another similar one substituted therefor readily and easily and without in any way affecting or changing 60 the intermediate furnace sections, as will hereinafter appear.

In the construction of a furnace of this kind, I preferably make the front and rear half sections relatively strong and heavy, 65 and I have provided means whereby prac-

tically all of the strains that are applied to a furnace of this kind are applied to said front and rear sections; hence the intermediate sections, hereinafter described, may be made relatively light and inexpensive. 70

In Figs. 6 and 9, I have illustrated one of the intermediate furnace half sections. Each of these is composed of a hollow upright body portion 35 having circulating openings 36 at its upper and lower portions 75 and having its inner side tapered inwardly at 37. On top is a lug 38 corresponding to the lug 15 and at the inner portion of the top is a lug 39 corresponding to the lug 29. The top of each of these intermediate half sections is indicated by the numeral 40 and its under surface is tapered downwardly at 41. Spaced apart from the top 40 is a horizontally arranged water chamber 42, the inner end of its top portion at 43 being flat 80 and being of substantially the same width as the body portion 35. Said top is provided near its outer portion with draft openings or notches 44 so that when two of these members 43 are placed together a 85 horizontal partition will be formed with draft openings at the notches 44.

To aid in the circulation of water from the water chamber 42 to the top portion 40, I preferably provide a hollow water chamber 95 45 communicating between these two parts. Below the body portion 35 is the flat downwardly extending flange 46 designed to rest upon a suitable furnace base or floor and also designed to form the inner 100 side of an ash pit.

In assembling these intermediate furnace half sections, I provide tapered push nipples 47, shown in Fig. 4, to enter the circulating openings and when the half sections are 105 drawn together by means of the bolts, these push nipples will be firmly seated and water tight joints made with the furnace sections.

In order to provide for the circulation of water through all of the boiler sections by 110 means of fittings that are applied only to the rear boiler section so that all of the strains are applied to the heavy rear section and not to the light intermediate sections, I insert in the upper circulating openings of 115 the rear section tapered pipes 48, which pipes are connected at their outer ends with the T-fittings 49 and these T-fittings 49 are connected by a pipe 50. At the bottom is a similar arrangement of pipes and T-fittings. 120 By this arrangement it is obvious that the heated water that rises to the top of each boiler half section flows into the pipe 50 and the cooled water returns through the corresponding pipe 51 at the bottom. By 125 this arrangement it is never necessary to apply any pipes for water circulation to any except the rear boiler section and when it is desired to use the furnace as a hot water furnace it is only necessary to provide some 130

means for carrying off the water from the pipe 50 and returning it after it has been used to the pipe 51.

If it is desired to utilize a furnace of this kind as a steam boiler furnace I simply remove the pipe connection between the pipes 50 and 51 and substitute therefor a steam chamber 52 which is extended from a point slightly below the pipe 51 to a point spaced 10 a considerable distance above the top of the furnace sections. This steam chamber is detachably connected with the pipes 50 and 51, by means of the fittings 50^a and 50^b. At the top of the steam generating chamber is 15 a steam discharge pipe 53 and the steam chamber may be provided with a water gage 54 and a steam gage 55.

In practical use, it is obvious that a great economy is effected by reason of my invention both on account of the fact that only 20 two patterns are needed for the construction of an entire furnace and also on account of the fact that the half sections may be handled much more readily and easily than 25 though entire sections were used extending across the furnace from side to side.

There is also a further advantage in forming a furnace of half sections because each half of the furnace is then made an independent water heating device and the objection 30 of cross currents flowing from one side of the furnace to another and thus short-circuiting a part of the furnace is avoided and each individual furnace half section is 35 so arranged that a complete circulation of water may be had therein.

Another very decided advantage in connection with my improved furnace construction is that half sections when placed in 40 position form a complete furnace and do not need any furnace wall or base on which to rest and hence when it is desired to change

the size of the furnace to either enlarge or reduce it this may be done without the necessity of building any masonry or cement furnace ash pits, or of providing a separate casting for an ash pit. When it is desired to convert a hot water plant of my construction into a steam plant the steam attachment is applied in the manner shown in Fig. 1, the 45 furnace is then filled with water level with the top thereof so that the water when heated in each furnace section will rise to the top, flow through the circulating openings 50 into the steam chamber and as soon as the 55 heated water reaches the steam space in the steam chamber steam will be instantly generated and will flow out through the steam supply pipe 53 at the top. The water when cool will return from the lower end of the 60 steam chamber into the radiator sections. Hence by means of this simple and inexpensive attachment a practical and efficient steam heating system may be made from a 65 hot water heater.

I claim as my invention:

In a sectional boiler an end section having water circulating openings and composed of identical interchangeable halves, each half being hollow and having a vertical side portion, a horizontal top portion and two intermediate horizontal portions, the walls of the portions being arranged to form an ash pit opening, a combustion chamber opening and a smoke chamber 70 opening, the walls of said last three openings 75 having a means formed thereon and located in the central plane thereof for supporting closure devices.

Des Moines, Iowa, Dec. 14, 1912.

CHARLES PHELPS.
